UNITED STATES PATENT OFFICE.

ELI A. MILLER, OF CONNEAUT, AND WILLIAM H. BROWN, OF NORTH KINGSVILLE, OHIO.

PUMP.

SPECIFICATION forming part of Letters Patent No. 324,401, dated August 18, 1885.

Application filed February 5, 1885. (No model.)

To all whom it may concern:

Be it known that we, ELI A. MILLER and WILLIAM H. BROWN, citizens of the United States, residing, respectively, at Conneaut and 5 North Kingsville, in the county of Ashtabula and State of Ohio, have invented certain new and useful Improvements in Pumps; and we do declare the following to be a full, clear, and exact description of the invention, 10 such as will enable others skilled in the art to which it appertains to make and use the same, reference being had to the accompanying drawings, and to the letters and figures of reference marked thereon, which form a part of 15 this specification.

This invention relates to pumps, and has for its object to provide improvements on the pump patented to Eli A. Miller, June 17, 1884, No. 300,623.

20 The present invention consists in certain novel features of construction, as will be hereinafter more fully described and claimed.

Referring to the drawings, Figure 1 is a vertical section of the well with the pump, &c., in place. Fig. 2 is a detail face view of the check-valve. Fig. 3 is a vertical section of the air-cylinder. Fig. 4 is a transverse section of same. Fig. 5 shows the air-cylinder in perspective. Fig. 6 is a detached section 30 of the piston.

As in the former patent, the air-cylinder A is arranged alongside the pump, which latter may be of any suitable form or desired variety—as lift, force, &c. We preferably provide the 35 cylinder A with plates A', to facilitate its application to the pump-stock.

The cylinder A has an opening, B, through its bottom, which is controlled by a valve, B', as will be understood from Figs. 3 and 4, which 40 will admit air on the upstroke of the piston and close the opening B in the downstroke thereof.

The piston C has its rod C' carried up and connected with the handle D' of the pump D, 45 so as to be operated simultaneously with the operation of the pump. We prefer to make piston C of elastic packing-rings E, held between metallic disks E', which latter are clamped against ring E, one above and the other 50 below, by nuts E' E'', turned on threads formed

on the piston-rod C'. By tightening one or the other of the nuts E' the packing-ring may be expanded to take up wear.

By reason of the swing of the pump-handle D' the piston-rod is not moved in a true line 55 up and down, but oscillates slightly. This requires that the hole F' through the top F of the cylinder be made larger than the piston-rod, to permit the oscillation thereof before described. This forms an enlarged opening, 60 through which dust and dirt may pass.

To prevent the ingress of dust or dirt we place on the piston-rod a disk, G, which rests down on top F, and is made large enough to cover the hole F', no matter at what point of 65 oscillation the piston-rod may be. This disk or plate G fits closely on the piston-rod, and is made of sufficient specific gravity to hold it down on the top F, on which it slides with the oscillations of the piston-rod; or it may be held 70 in suitable guides on said top, as will be understood.

The port B is the inlet-port. The outlet-port H is formed laterally through the cylinder, near its bottom, and communicates with the 75 connection H', being suitably controlled by the check-valve I. This valve I is preferably formed of a disk of leather, rubber, or other pliable material, having its outer edges clamped between the connection H' and the cylinder. 80 The central portion of this disk which fits over the port H is imperforate, and it is provided, without the area of said port H, with perforations I'. The valve I, it will be seen, is formed with an outer ring, an inner imperforate portion 85 or disk, and strips i, connecting the said ring and central portion or disk. On the upstroke of the piston the valve I is drawn closely against and closes port H. On the downstroke of the piston the valve is forced out away from 90 port H, and the air passes off through openings I', as will be understood.

The pipe J is connected at its upper end by L H' with the air-cylinder, and depends 95 thence into the well.

A suitable air-discharge, K, is formed through the curbing, so as to permit the proper circulation of air out of the well as fresh air is forced thereinto by the air-pump.

In the former patent, above referred to, we 100

have described the advantages attending the forcing of air into the well. In addition there-
to we have found it desirable to force the air directly into the water, as by so doing the
water becomes aerated and more palatable.
5 In carrying out this project, experience has demonstrated that when the pipe projects straight down into the water and is open at its lower end the air forced therethrough into
10 the water produces a current of water, which, striking the bottom of the well, stirs up the accumulated sediment and mud, rendering the water thick and undesirable for use. To ob-
viate this objection we turn the lower or dis-
15 charge end J' of the air-pipe so that it will not direct the air toward the bottom. This turning may be only at a right angle; but in such case a current would be directed against the side of the well, which, in some cases, is
20 also full of sediment, which will be stirred up by the current of water. We prefer, therefore, to turn the end of the pipe so that its open end will project upward, thus directing all currents produced by the air-discharge di-
25 rectly up toward the surface of the water. This arrangement, it will be seen, will not produce any currents likely to disturb the sedi-

ment, mud, &c., and yet accomplishes the de-
sired end in an efficient manner.

It is manifest that the upturned end of the 30 air-discharge pipe would give good results in an open well without a pump; but we prefer to use it in connection with a pump, as thereby the simultaneous operation of the air and water pump is secured, and the air-pump is 35 certain to be properly and sufficiently worked to give the desired results.

Having thus described our invention, what we claim, and desire to secure by Letters Patent, is—

40 The device hereinbefore described for aerating water in wells, consisting of an air-pump and a discharge tube extended downward from the air-cylinder, and adapted to enter the water in the well, and having its lower end turned upward, substantially as and for the purposes set forth.

45 In testimony whereof we affix our signatures in presence of two witnesses.

ELI A. MILLER.
WILLIAM H. BROWN.
